UNITED STATES PATENT OFFICE.

ARTHUR B. DAVIS, OF ELKRIDGE, MARYLAND.

HINGE FOR ELECTRIC APPARATUS.

SPECIFICATION forming part of Letters Patent No. 531,515, dated December 25, 1894.

Application filed May 12, 1894. Serial No. 510,972. (No model.)

To all whom it may concern:

Be it known that I, ARTHUR B. DAVIS, a citizen of the United States, residing at Elkridge, in the county of Howard and State of Maryland, have invented certain new and useful Improvements in Electric Conductors, of which the following is a specification.

My invention relates to an improvement in electric conductors for use in connection with electrical instruments inclosed in casings where one or more members of said instruments are carried by the swinging door of the casing, and where it is necessary to establish electrical connections between the member in the casing and that on the door. It is desirable in such cases to make the connection through one or more of the hinges which join the door to the casing and this has been done heretofore by attaching the ends of the circuit wires on either side of said hinge to respectively the two leaves of the hinge and thus the hinge itself forms the desired connection, but it has been found in practice that a good electrical connection cannot always be made in this manner, first, because the parts of the joint between the leaves of the hinge are not sufficiently binding upon each other to insure a good contact, and, second, because the pintle of the hinge ordinarily made of iron or steel oxidizes, which has the result to insulate the two leaves of the hinge from each other.

The object of this invention is to substitute for the usual pintle of iron, a pintle of some metal which is non-oxidizable, and at the same time is a good conductor of electricity.

In the accompanying drawings,—Figure 1 shows a portion of a casing and the lid hinged thereto by a hinge constructed according to my invention and showing the method of connecting the wires. Fig. 2 is an end view of the hinge constructed in accordance with my invention. Fig. 3 shows a section of the hinge on line 3—3 of Fig. 2. Fig. 4 is a view similar to Fig. 3 and showing a modified form of my invention.

In the drawings the letters, A, A', indicate the leaves of the hinge of which, A, is fastened to the side of the casing, B, and A' is fastened to the lid, C, of the casing. The pintle, D, is made of some metal which is malleable, non-oxidizable and a good conductor of

electricity. The preferred metal is phosphor-bronze which has been found by experiment to possess these properties to a high degree. 55

The hinge is especially constructed as follows: After the leaves are formed a reamer is passed through the knuckles thereof, or in some equivalent manner the inner side or bore of the knuckles is made bright and 60 clean. The said knuckles of the two leaves are then fitted together and the pintle, D, inserted. As made the pintle is primarily somewhat longer than the leaves in order that when the said pintle is inserted through the 65 bore its ends may be pounded so as to be upset, shortened or expanded inside the bore or joints and closely fill the spaces or interstices thereof. In this manner the pintle forms a continuous conductor from one leaf 70 to the other. The malleability of the metal pintle permits it to expand while its non-oxidizable properties insures a good electrical contact between the pintle and the two leaves of the hinge. 75

The current passes through the wire, a, to the leaf, A, from there through the pintle, D, to the other leaf, A', and from there along the other wire, a', which wires are confined by the screws, b, by which the leaves are fastened to the casing. 80

Fig. 4 illustrates a modification. In this instance the pintle is not expanded in the hinge joints but extends beyond the ends of the leaves and each leaf has a spring contact 85 arm, E, confined thereto at one end by one of the fastening screws, b', and the other end binds against and makes contact with the projecting end, c, of the said pintle. The electric current passes from the wire, a, through the 90 spring arm, E, on the leaf, A, to the pintle, D', and through the pintle to the other spring arm, E, on the leaf, A', and then to the wire, a'. 95

I am aware of the patent to Watson, No. 221,434, which shows a flat spring fastened to one leaf of the hinge and adapted to contact with the other leaf. I am also aware of the patent to Wilson, No. 352,596, which shows a somewhat similar construction. Both of these patents have the same end in view but employ different methods of accomplishing the results aimed at in my invention, which provides a permanent constant conductor and at the same time a practical hinge. 100

Having thus described my invention, what I claim is—

- 5 1. In an electrical conductor, the combination of the leaves, A, A', of the hinge; a pintle of non-oxidizable material connecting the two leaves of said hinge; and two circuit wires, a, a', attached to the leaves and in electrical connection with said pintle.
- 10 2. In an electrical conductor, the combination of the leaves, A, A', of the hinge; a pintle of non-oxidizable, malleable material expanded inside the bore or joints of the leaves to fill the interstices thereof; and electric circuit wires connected with said leaves.
- 15 3. The combination of a box to contain elec-

trical instruments and provided with a lid or cover; hinges having two leaves, A, A', secured, respectively, to the box and cover; a pintle of non-oxidizable, malleable material expanded within the bore or joints of the hinge to fill the interstices thereof; and circuit wires, a, a', in electrical connection with said leaves, substantially as described. 20

In testimony whereof I affix my signature in the presence of two witnesses.

ARTHUR B. DAVIS.
